UNITED STATES PATENT OFFICE.

SAMUEL H. COWLES, OF BUFFALO, NEW YORK.

DESIGN FOR A SCALE-PLATE.

SPECIFICATION forming part of Design No. 30,470, dated April 4, 1899.

Application filed September 14, 1898. Serial No. 690,981. Term of patent 7 years.

To all whom it may concern:

Be it known that I, SAMUEL H. COWLES, a citizen of the United States of America, and a resident of Buffalo, in the county of Erie 5 and State of New York, have invented and produced a new and original Design for a Scale-Plate, of which the following is a specification, reference being had to the accompanying drawings, forming part thereof.

Figure 1 is a face view of a dial, showing my design. Fig. 2 is a sectional view through *x x* of Fig. 1.

As shown in the drawings, the general outline of my design is that of a circle from 15 which a segment of substantially sixty degrees has been removed, resulting in a boundary-line comprising a straight base *a*, from which springs the curvilinear portion or arc *b*. Concentric with the arc *b* is represented a 20 circle *c*, inclosing a clock-face *d*, comprising Roman numerals and minute-divisions. Exterior of the circle *c* and upon the face of the design concentric with the arc *b* are drawn two arcs *e* and *f*, connected at their ends by 25 straight lines *g* and *h* parallel with the bound-

ary-line *a*. Springing from the inner arc *e* and crossing arc *f* are drawn a series of radiating lines *i*, which coincide with lines that might be drawn radially of the clock-face and passing through the numerals marking the 30 hours. Equidistant from each pair of lines *i* are additional radiating lines *k*, which cross the arc *f* and terminate between it and the arc *e*. The spaces between lines *k* are bisected by broken lines *m*, each comprising 35 two elements, of which one lies outside the arc *f* and the other extends inwardly therefrom. The spaces between the outer elements of the broken lines are bisected by dots *n*, as shown.

Having described my invention, what I claim, and desire to secure by Letters Patent, is—

The design for a scale-plate as herein shown and described.

SAMUEL H. COWLES.
